FOREIGN PATENT DOCUMENTS

FR 2811606 1/2002

* cited by examiner

Primary Examiner — Patricia Palasik(74) *Attorney, Agent, or Firm* — Michael Best & Friedrich LLP(57) **CLAIM**

I claim the ornamental design for a wood boring bit, as shown and described.

DESCRIPTION

FIG. 1 is a perspective view of another embodiment of a wood boring bit.

FIG. 2 is a front view of the wood boring bit shown in FIG. 1; and,

FIG. 3 is a left side view of the wood boring bit shown in FIG. 1.

The elements shown in broken lines are included for the purpose of illustrating environment and form no part of the claimed design.
